MOX TOY HUW, OF NEW YORK, N. Y.

COMPUTING-SCALE.

1,129,095.

Specification of Letters Patent. Patented Feb. 23, 1915.

Application filed May 14, 1913. Serial No. 767,579.

To all whom it may concern:

Be it known that I, Mox Toy Huw, a citizen of the United States of America, and resident of New York, in the county of New York and State of New York, (whose post office address is No. 12 Pell street, New York, N. Y.) have invented certain new and useful Improvements in Computing-Scales, of which the following is a specification.

This invention relates to improvements in calculating apparatus, such as computing scales, for indicating relations between a weight factor and a price factor.

One of the principal objects of this invention is to provide an apparatus which will be accurate, efficient, and capacitated for controlling and selectively exposing a legible indicium irrespective of the number 20 of indicia utilized and possible of selective exposure.

Another object is simplicity and compactness of construction.

While attention is called particularly to the structural features and the various adjustments, it should at the outset be understood that the invention has reference not only to computing apparatus, but also to testing or tension apparatus, and of course 30 to all improvements within the scope and spirit of the invention as it is set forth in the claims.

In the accompanying drawings, which are to be taken as a part of this specification, and in which I have shown a form of embodiment of the invention as at present preferred: Figure 1 is a front elevation, partly broken away, of one embodiment of this invention; Fig. 2 is a cross-section on 40 the line 2—2 of Fig. 1, looking from right to left; Fig. 3 is a detail of an adjustment for the indicating cord; Fig. 4 is an elevation of the same; Fig. 5 is a detail of one of the revolving indicators or drums; Fig. 45 6 is a view taken on the line 6—6 of Fig. 5; and Fig. 7 is a view similar to Fig. 5, but illustrating another and possible method of mounting one of the revolving indicators or drums.

Similar reference characters refer to similar parts throughout the several views of the drawings.

Referring to the numerals on the drawings, 7 is a casing or cover, preferably made 55 of sheet brass or other suitable material, within which are located and mounted the

various mechanisms to be hereinafter more fully described.

8 is a hook passing through the aperture 9 at the upper extremity of casing 7 and 60 being fastened to the transversely extending bar 10, which may be riveted to the casing 7 as shown at 11 and 11' in Fig. 1.

12 and 12' are angle beams resiliently connected to bar 10 by means of the springs 65 13. At the right and left hands of beams 12 and 12' are flanged portions 14 to which are fastened the strips 15 serving to reinforce said beams, and also to form a support for the vertical rods 16 extending 70 downwardly through the apertures 17 and 18 at the lower extremity of casing 7. 19 is another beam connecting the rods 16 outside of the casing 7. From this it will be clearly understood that the beams 12 and 75 12', rods 16 and beam 19 form a rectangular frame, which, as a unit, will operate against the tension of spring 13, when a load or weight is applied at the hook 20 attached to the beam 19.

Referring now particularly to Fig. 2, it will be observed that the rods 16 have rack portions 21 and 21' meshing with gears 22 and 22', which in turn are rigidly fastened to what will hereinafter be referred to as 80 indicia-bearing members 23 and 24, said members 23 and 24 in this embodiment comprising drums that are rotatably mounted upon shafts 25 and 26, respectively, and consisting of a hub at each end, and radial ribs 85 90 extending to a cylindrical body upon the circumferential surface of which is attached in any well-known manner a printed sheet of paper or the like carrying, in transverse columns, first, weight indicia, appearing at 95 the extreme left of the drums, and following that, in columns from left to right, indicia of prices.

It will also be observed that the index cords 28 and 29 extend parallel to and in 100 the same horizontal plane with the axis of indicating members 23 and 24, and have a terminus at each end in casing 7. Attention is momentarily called to Figs. 3 and 4, in which the cord 28 is shown as being anchored to pins 29'. This pin may be shifted in slots 30 in order to adjust the cord 28 in case it should not be in proper horizontal alignment with the numerals on the indicating member or drum 23.

31 is a tension spring which will always 110 keep the cord 28 taut.

In the casing 7, immediately in front of cords 28 and 29, are elongated slots each provided with a window 32 of glass or other transparent material firmly held to the casing 7 by the strips 33. Scales such as 34 are fastened between the glass plate 32 and the strips 33, said scales having numbers in a horizontal row, advancing arithmetically from left to right as shown, and aligned vertically with the price columns on the drums.

35 are segments pivoted on the shafts 36 having extension rods 37 upon which counter-weights 38 are adjustably secured.

39 are plates forming a circumferential 15 guide for the chains 40, which in turn are anchored between beams 12 and 12'.

In the modification shown in Figs. 5 and 6, the shaft 26 terminates in a socket 41 held firmly against the casing 7 by the wing-nut 20 42 allowing for lateral adjustment in the slot 43.

In the modification shown in Fig. 7, the shaft 26 terminates in an integral spindle and ball-impinging shoulder as shown; the 25 spindle being journaled in the exteriorly threaded socket 44 mounted as illustrated in the casing 7 in such manner that a ball-bearing, via the balls 45, is established for the shaft.

30 The operation of this embodiment of this invention, which should largely be obvious, is substantially as follows: Upon applying a load to the hook 20, the rectangular frame (12, 12', 16 and 19) descends through the 35 apertures 17 and 18, thereby rotating the gears 22 and 22' in the direction of the arrows, thereby rotating the indicia-bearing members 23 and 24, in opposite directions to a point where the load equalizes the tension 40 of spring 13, thereby causing a stop. If this load is, say, seven pounds, the indicia-bearing members 23 and 24 will both assume the position illustrated in Fig. 1, and if the price per pound of the load applied is, say, 45 twenty-five cents, the cost of seven pounds at twenty-five cents per pound will be indicated on the drum 28 in the price column that corresponds with the number "25" on scale 34, so that a cost of \$1.75 for the seven 50 pounds, at twenty-five cents per pound, is indicated. Of course fractions may be used as well as units, although, for the sake of clearness, they are not shown. The beams 12 and 12' in descending pull the chains 40 55 down, acting against the counter-weights 38. In this manner there will be in addition to the tension of the spring 13, an additional adjustable weight which can be varied according to the wear of this apparatus, or if 60 the spring 13 should in time lose some of its tensional properties, due for instance to imperfect tempering, the counter-weights 38 may be shifted down on the rods 37 thereby giving said rods a longer leverage and increasing the momentum of the pendulum 65

effect. After releasing the load from the hook 20, the spring 13 will withdraw the rectangular frame (12, 12', 16 and 19) to its normal position so that the indicia-bearing members 23 and 24, and simultaneously the 70 counter-weights 38, will return to normal position due to gravity. In this way the chain 40 will naturally always be under a slight tension. There is also an advantage in the employment of the spaced rods 16 75 with their respective racks and the pinions engaging the said racks, for by reference to Fig. 2, it will be evident that the pinions thus have opposite bearings on the rectangular frame and in effect constitute roller 80 bearings for said frame that tend to prevent lateral movement of the same in either direction and obviate any binding action with consequent friction.

It will be evident that by the provision 85 of any desired plurality of drums it is possible to make a machine that will cover a practically infinite range of weights and prices, without increasing the horizontal extent of the device, and without impairing 90 legibility. At the same time, the machine is well balanced, because of the manner in which operating strains are evenly distributed with reference to the point of suspension.

Inasmuch as many changes could be made in the above construction, and many apparently widely different embodiments of my invention could be made without departing 100 from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention, which, as a matter of language might 110 be said to fall therebetween.

Having described my invention, what I claim as new and desire to secure by Letters Patent, is:—

1. In apparatus of the character set forth, 115 the combination with a support and scales mounted thereon, of oppositely rotatable indicia carrying members journaled in the support and cooperating respectively with the scales, pinions connected with the rotatable members, and a frame movably mounted in the support and having oppositely disposed racks respectively in mesh with the pinions and being held thereby against substantial lateral displacement.

2. In apparatus of the character set forth, 120 the combination with a support and scales mounted thereon, of oppositely rotatable indicia carrying members journaled in the support and cooperating respectively with 125

130

- the scales, pinions connected with the rotatable members, and a frame movably mounted in the support and including spaced substantially parallel rods located on opposite sides of the pinions and having racks on their inner sides that respectively engage the pinions, said rods being thereby held against substantial lateral movement in either direction.
- 10 3. In apparatus of the character set forth, the combination with a casing having an upper and a lower view opening and scales located alongside the same, of upper and lower indicia carrying drums within the casing behind the view openings, pinions on the ends of the drums, a frame slidable in the casing and having spaced rods located on opposite sides of the pinions, and racks on the inner sides of the rods, each rack meshing with one of the pinions substantially preventing lateral movement of the frame.
- 15 4. In apparatus of the character set forth, the combination with a casing having an upper and a lower view opening and scales located alongside the same, of upper and lower indicia carrying drums journaled within the casing behind the view openings and having substantially parallel axes of rotation, pinions on the ends of the drums,

a vertically slidable frame in the casing having sets of spaced rods located at the ends of the drums and on opposite sides of the pinions, and racks on the inner sides of the rods, each rack meshing with one of the pinions.

5. In apparatus of the character set forth, the combination with a casing of a pair of fixed scales arranged one above another, a frame bodily and vertically movable transversely of the scales, a weight-supporting means connected to the frame, a pair of indicia-carrying members each rotatively supported in the casing adjacent one of the fixed scales, a separate pinion carried by each of said members, a rack member carried by the frame, whose teeth mesh with the said pinions, said pinions being in vertical alignment, and the rack member including two series of vertically arranged rack teeth, each series of teeth being adapted to coöperate with one of said pinions, and one series of teeth being vertically offset from the other.

In witness whereof, I have hereunto signed my name in the presence of two witnesses.
